UNITED STATES PATENT OFFICE

ROBERT S. PEELLE, OF HOLLIS, NEW YORK, ASSIGNOR TO THE PEELLE COMPANY, OF NEW YORK, N. Y., A CORPORATION OF NEW YORK

DOOR OPERATOR

Application filed September 10, 1929. Serial No. 381,526.

My invention relates to door operators, and more particularly to operators for doors of the counterbalanced type.

Heretofore it has been a common practice to provide counterbalanced doors in an elevator shaft with an electrical operator arranged in the penthouse and controlled from a car or from the floor of a building, which operator was selectively operative as to any of the doors in the shaft for the purpose of closing and sometimes also opening same by power.

Electrical operators have also been used which consisted of an electric motor mounted upon the floor side of the wall of a shaft, and geared to the sheaves about which the flexible connections of a door passed, each door being provided with such a motor and such gearing.

Door operators of the type above referred to, in which each door is equipped with a motor, have been found to be very expensive equipment because of the necessity for having the motor and the gearing actuated thereby for rotating the sheaves, upon the floor side of the shaft, the sheaves themselves being located upon the shaft side of said wall. Furthermore, all types of electrical operators above referred to required limit stops actuated by each door, or by a moving part of the actuating mechanism, or the exercise of extreme care by the attendant when either opening or closing the doors, to prevent overrunning of the motor and possible resultant injury to the doors or to the motor.

My present invention embodies some of the characteristics of each type of door above specified, in that each door in a shaft is provided with its own motive power for opening and closing same, but the actuation of the various motors is selectively controlled by a mechanism in the penthouse in conjunction with mechanisms in the shaft and in the elevator car.

In an operator embodying the invention, the construction is such that the motors for imparting opening and closing movement to the door may be located within the shaft, each motor being geared directly to a sheave, so that no openings through the wall need be made when installing the operator. These

motors are connected in parallel with a source of electrical supply so as to ensure simultaneous movement of both sheaves.

By using two motors as above described, the horsepower of each motor may be very low, since the total load which must be carried by both motors is equal merely to the difference in weight between the two sections of a door, which will never be more than a few pounds, and may even be negligible.

The mechanisms used for controlling the application of power to these motors are such that while a single electrical control mechanism may be used in the penthouse, the operative effect of setting this mechanism, by means of a switch upon the car, on a floor, or for the micro-mechanism, will be merely to cause power to be applied to the motors of one door, the circuits to the motors of all other doors in the shaft remaining open.

The manner of connecting the doors is such that no exactitude in the timing of the operation of the motor is required, since the operative effect of the motors upon the door is determined by the opposed weight of the two sections. I provide, however, a master limit switch as a part of the control mechanism in the penthouse, by means of which a time limit is placed upon the operation of the control switch mechanism as a whole during the opening movement of the door only, so as to preclude any possibility of overrunning of the upper door section in a manner to cause injury to the sheave structure and the motors.

The electrical control mechanism is so constructed that under normal working conditions, when it is desired to open a door, the closing of the opening switch in the car, or on the floor, or of the micro-mechanism control, will establish an electrical condition which will continue for the full interval of the time for which the master limit switch is set. A constant pressure switch, however, is used for maintaining the control mechanism in operative relation during the full closing movement.

The arrangement of the control mechanism is also such that if desired, all of the control switches may be made inoperative while power is being applied to the motor for operating

the elevator car. This arrangement is for use with installations in which the elevator is run without an attendant on the car, for the purpose of preventing the stoppage of the car and the opening of the doors of one floor while the car is operating under controls from another floor. In the elevator door operator of my invention, this feature forms a part of the control mechanism for operating the doors and has nothing to do with the controls for the elevator car itself.

The invention consists primarily in a door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with a sheave, gearing connecting said motor with its associated sheave, a main electric power line extending adjacent all of said doors, a branch line extending therefrom adjacent each door and connected with the motor adjacent such door, a normally open switch in said branch line, means carried by an elevator car adapted to co-operate with any of said normally open switches, whereby the circuit from said main line to a motor operative upon any door can be closed only when a car is positioned adjacent said switch, pole changing switches controlling the circuits to said main power line, electro-magnetic control mechanisms for said pole changing switches, and means whereby said control mechanisms may be selectively actuated from a remote point; and in such other novel features of construction and combination of parts as are hereinafter set forth and described, and more particularly pointed out in the claims hereto appended.

Referring to the drawings,

Fig. 1 is a view of an elevator shaft door equipment vertically and laterally condensed, with the penthouse switch and control mechanism indicated conventionally;

Fig. 2 is a side view from the right of Fig. 1 and upon a larger scale, showing one sheave mechanism and its motor;

Fig. 3 is an electric diagram showing the penthouse switch and control mechanism, the various remote controls for the circuit and the actuating motor circuits for a single door; and

Fig. 4 is a horizontal section above a door, the door being in an open or partially open position.

Like numerals refer to like parts throughout the several views.

The operator of my invention is for use in positively opening and closing freight elevator doors of a type well known as "counterbalanced" doors, the detailed construction of which doors is immaterial to the invention.

In the drawings, I have illustrated two doors of a series in a shaft, each door being actuated by its own individual motors, the power to these motors being controlled by a switch mechanism ordinarily positioned in the penthouse, actuating means operative thereon and a remote control of the actuating means for the switch mechanism, which ordinarily is located in the elevator car, but may also be located on the floor of a building or adjacent the power actuating mechanism for the car.

In describing the invention, I will first refer briefly to essential characteristics of counterbalanced door installations, then to the arrangement of parts for opening and closing any selected door, and finally to the electrical conditions for controlling the application of power to the door opening and closing mechanism, incidental reference being had to the movements of the car without a detailed description of the same.

In counterbalanced elevator doors, as shown in the drawings, a continuous guide rail structure is positioned upon the inner wall of the shaft at each side of the door openings, each guide structure comprising a wall angle 10 having secured thereto a guide angle 11. Each door consists of two sections, each of approximately the same weight as the other, although either section may be over-weighted as compared with the other.

In the drawings, the upper section of the upper door is indicated at 12, and the lower section at 12a. In the lower door shown, the upper section is indicated at 13, and the lower section at 13a. Each lower section 12a and 13a has the usual hanger bar and truck rail structure indicated at 14 as to each door, the ends of which project across and beyond the guide rail structure so as to engage what is known as trucking stops 15 secured to the wall angle 10 of each guide rail structure.

During the opening and closing of the door, the two sections are vertically and oppositely movable by reason of the use of connections between the sections which ordinarily consist of a turn buckle bar 16 connected with the hanger bar of the lower door section, and a link chain 17 connected adjacent the lower edge of the upper door section, the hanger bar being a part of the top bar of the lower door section. The chain 17 at each side of a door passes over a sheave 18, a housing for which is secured to the wall angle, the axis of this sheave being perpendicular to the wall of a shaft, and the sheave in its entirety being positioned at one side of the path of movement of the upper door section in order to permit the opening and closing movement of this section.

Ordinarily, when it is desired to permit the automatic actuation of such doors, a locking mechanism is used which may be actuated from the car and which co-operates with the

hanger bar of the lower door section at each side of the opening. Such a locking mechanism is shown conventionally at 19, but this locking mechanism is not essential to a door equipped with the operator of my present invention.

The connections, sheave and lock mechanisms above described are duplicated upon opposite sides of each door.

10 The wall of the elevator shaft about the door openings is shown at 20. The bracket supporting the sheave housing is shown at 21.

15 The parts and mechanisms above described merely relate to one well known type of elevator door, and are subject to wide variation with modifications of this type of door.

20 My present invention has to do with a power mechanism associated with each door by which both opening and closing movement may be imparted to that door, the mechanisms associated with the various doors receiving their power from a common source selectively controlled so as to limit its operative effect to a particular door opening.

25 The use of individual, separately controlled operators for each door in a shaft is old, the present invention relating to a particular construction and arrangement of the power operating mechanism in relation to the door, and 30 the means for controlling the application of power to any such mechanism.

As shown in the drawings, my invention involves the use of two small electric motors secured to the door guide structure which includes the guide angles 11, the wall angles 10 and the plates 21 respectively. Since the sections as 12-12a of a door are approximately balanced as to weight, it is obvious that each of these motors may be of very low H. P. 40 the size of motor being largely determined by the dimensions and weight of the doors and possible variation in the weights of different sections of the door. With the ordinary door, I have found that a motor of $\frac{1}{6}$ H. P. is adequate to meet the varying demands of a standard equipment and allow a sufficient margin of safety. This motor is set with its shaft perpendicular to the wall of the elevator shaft.

50 The motor to the right of the door, as seen from the inside of the elevator shaft, is indicated at 22, and that to the left, at 23. The shaft of the motor 22 is indicated at 24, and that of the motor 23 at 25.

55 Upon the shaft 24 is mounted a small gear 26, enmeshed with a large gear 27 which is permanently secured to the flange of the sheave 18 positioned toward the wall of the elevator shaft. The motor 22 is set as close to the gear 27 as is practical so that it may be as nearly as possible, positioned in its entirety within the shaft. With narrow doors, however, it may be necessary for the erection gang to form a recess in the wall to accommodate a part of the motor, as shown in Figs.

2 and 4 of the drawings. This condition is particularly true when thin doors are used, although when thicker doors and larger wall angles are used it may be possible to avoid the cutting of the wall.

70 The ratio of the gears 26 and 27 may vary, it being necessary, however, in the design of the operator, to provide for a speed reduction to avoid a too rapid movement of the doors when opening or closing same. The gear 27 preferably is of a diameter approximately that of the flange of the sheave.

75 The shaft 25 of the motor 23 carries a small gear 28 corresponding with the gear 26 which meshes with a gear 29 corresponding with the gear 27 and secured to the sheave 18 with which the motor 23 is associated.

80 Spur gears are used in order to effect a rapid opening and closing of the door.

85 Both motors are reversible and may be of any desired design, it being essential of course that each shall have substantially the same speed as, and be so wired as to normally turn in a direction opposite to that of, the other.

90 It is to be noted that each of the motors 22 and 23 is positioned without the path of movement of the upper door section as 12 or 13, and that the gearing connecting same with the sheave with which the motor is associated is also without the path of such movement.

95 One of the difficulties in the use of individual operators for elevator doors of the counterbalanced type has been the impossibility of using a gearing for operating the sheaves positioned upon the shaft side of the wall of the elevator shaft which can simultaneously act upon both sheaves. These sheaves being located in substantial alignment with the plane of movement of the upper door section, and closely adjacent the top of this section, any attempt to use mechanical gearing connecting the two sheaves would require the locating of this gearing within the plane of movement of the upper door section, which is impossible.

100 Elevator doors of the counterbalanced type are used because they occupy very little space in the shaft. The face of the doors presented toward the shaft is set so close to the wall as to present no space, between the plane of movement of the door and the wall, in which to locate gearing passing across from one guide rail to the other. On the other hand, the shaft side of the doors is located so close to the plane of movement of the front edge of the elevator car, that no space is afforded between the door and the car platform for the location of such mechanism. Furthermore, even if a shaft could be run across the elevator shaft above a door opening, the gears carried by this shaft would project to an extent to interfere with the travel of the car. It is for this reason

that heretofore, in one type of door operating mechanism, a single motor and connecting gearing between same and the two sheaves of a door were always located upon the floor

• side of the shaft wall and connected with the sheaves by means of a shaft passing entirely through the wall.

In an operator embodying my invention, the motors and the gearing connecting same with the sheaves of a door, are not only in their entirety within the shaft, but within the space occupied by the door and the guide rail structure, and the labor of piercing the wall and accurately setting the shaft connecting the gearing with the sheave is avoided.

The electrical system forming a part of the operator will vary with the type of motor used and the character of the current. In the drawings I have shown multiple-phase, A. C. motors. With this type of installation, I employ a main electric power line having three wires 30, 31 and 32 which extend throughout the entire height of, and adjacent all doors in, the shaft. Adjacent each door there are three branch lines 33, 34 and 35 connecting in parallel the two motors 22 and 23, the connections being such, however, that said motors are, with the closing of the circuit of the main power line, rotated in opposite directions, see Fig. 3.

Controlling the circuits to said main power line is a pole changing switch mechanism consisting of two groups of three switches each, the closing of one group of switches applying power to the motors 22 and 23 under a suitable control, which will later be described, to cause a rotation of the motors 22 and 23 in a direction to cause the sheaves 18 to raise the upper door section and permit the lower door section to descend. The other group of switches, when closed under suitable control, will cause a reversal of the direction of rotation of the motors 22 and 23, and of the sheaves 18, thus raising the lower section which will permit the upper section to descend.

The first group includes switches 36, 37 and 38, one of the contacts of which is connected with the main power line through leads 39, 40 and 41, and the other contact of which is connected through lines 42, 43 and 44 to the source of power through lines 45, 46 and 47. The other group, which is used for controlling the power for closing the door, consists of three switches 48, 49 and 50 which are connected by lines 51, 52 and 53 with the lines 40, 39 and 41 respectively, and therethrough with the main power lines 31, 30 and 32 respectively, thus causing the reversal of the polarity of the lines 30 and 31 of the main power line when the closing switch mechanism is actuated as compared with when the opening switch is actuated.

• The switches 36, 37 and 38 I shall design-

ate "door opening switches", and the switches 48, 49 and 50 I shall designate "door closing switches".

With the electrical system shown in the drawings, one of the wires of the main power line as 30 is in constant connection with both motors 22 and 23, either through the line 35 or through a lead line as 35a, as to the motor 22. The branch lines 33 and 34 are also adapted to be connected with both motors, either directly or through the lead lines 33a and 34a, as to the motor 22, by means of a normally open switch mechanism 54, which I shall call a "shaft switch", having fixed contacts communicating with the wires 31 and 32 respectively through the electrical connections 33b and 34b, and contacts carried by a movable contact member 55, which contacts are in direct electrical connection with the branch lines 33 and 34. A shaft switch 54 is located adjacent each door in a shaft and is adapted to be actuated by a shoe shown conventionally at 56 which is carried by the elevator car. This shoe may be a fixed shoe or a receding shoe as desired.

It will be noted that the use of the shaft switch 54, in the branch lines from the main circuit leading to the motors operative upon the respective doors, will prevent the application of power to the motors operative upon all doors in a shaft, even though a door opening or closing switch in the main power line may be closed. In other words, the main power line will remain dead at all times, unless one of the shaft switches 54 is closed, notwithstanding the actuation of the door opening or closing switches.

Each of the door opening or closing switches controlling the circuit from the source of power to the main power line has an actuating means, which includes what is known as holding circuits, and electro-magnetic control mechanisms, one for each group of switches.

The actuating means for the door opening or closing switches comprises two electromagnets 57 and 58, the armature 59 of the former of which is operative upon the movable contact members 36, 37 and 38 of the door opening switch, while the armature 60 of the latter of which magnets is operative upon the movable contact members 48, 49 and 50 of the door closing switch.

These magnets may be energized from the main source of power through remote control switches, one of which is located in the elevator car, and others of which may be located at different floors of a building, in the penthouse or in the engine room, as desired.

These different remote controls are selectively operative, and the actuation of any control will have the same operative effect as to the application of power to the motors for opening or closing a door.

I will first describe the control switch mechanism in the elevator car called the car switch and the various circuits controlled thereby, first for opening the door and then 5 for closing the door.

The car switch is shown at 61 and includes a normally open opening switch of the usual or any desired construction indicated at 62, a normally open closing switch 63 and a normally closed stop switch 64. These are bridge switches, and one of the fixed contacts of each switch is in electrical connection with a fixed contact of both of the other switches as by means of wires 65 and 66. In 10 this manner the circuits controlled by the switches 62 and 63 can be closed only through the holding switch 64, so far as their operative effect upon the electro-magnets 57 and 58 is concerned.

One terminal of the electro-magnet 57 is in electrical connection through the lines 67 and 68 with the line 42, and the other terminal is in electrical connection with the line 44 through the line 69, the opening switch 62, the wires 65 and 66, the normally closed stop switch 64 and the line 70. The contact of the stop switch 64 with which the wire 66 is connected, is in electrical connection through the line 71 with the winding 72 of an electro-magnet forming a part of what is known as a master time limit switch 73, the mechanisms of which are indicated conventionally. This time limit switch contains normally closed contact members 74, one of which is connected with the winding of the electro-magnet 72, and the other of which is connected by the line 75 with a fixed contact of a switch 76, the movable contact of which is acted upon by the armature 59 and is in 20 electrical connection through the lines 77 and 69 with the winding of the electro-magnet 57.

The time limit switch 73 is specifically not my invention, but may be obtained upon the open market in various forms, it being old 25 and well known in the art. I will therefore describe it merely generally and have shown it merely conventionally.

In one form of master time limit switch, the electro-magnet 72 is a solenoid, the core 50 of which is connected with a cross bar 78 having two rods 79 and 80, the first of which acts upon a compression spring 81, and the second of which is connected with the plunger of a dash pot 82. This dash pot is so constructed as to resist the movement of the plunger outwardly of the dash pot cylinder which is provided with an adjustable vent opening by which this resistance will be gradually decreased, for an interval determined by the size of the opening, until the plunger has moved a predetermined distance necessary to open ports through the cylinder of the dash pot and thus instantly relieve the sub-atmospheric pressure within the cylinder and permit the free movement of the plunger.

The movable contact member of the normally closed switch 74 is carried by an oscillatory lever 83, one arm of which is acted upon by the spring 81, and the other arm of which is acted upon by a spring 84 opposed to the 70 spring 81. The operative effect of this spring 84 is to normally overcome the tension of the spring 81 and close the contacts of the switch 74.

One terminal of the winding of the magnet 75 58 is in electrical connection with the lines 68 and 45. The other terminal is in electrical connection through a line 85 with one of the fixed contacts of the closing switch 63, the other fixed contact of which is in electrical 80 connection through the wire 66, the stop switch 64 and the line 70 with a plus line such as 44.

The circuits heretofore described have particular relation to the control of the door 85 opening and closing switches by the car switches.

In addition to so controlling said door opening and closing switches by the car switches, they may be also controlled by the micro-mechanism control, whether the same be manual or automatic and by what is known as floor control switches, which may be actuated from the floor side of the shaft.

When it is desired to actuate the door as a 95 result of the actuation of the micro-mechanism control, I provide a normally open switch mechanism 86, the fixed contact of which is connected to the line 44 by the line 87, and the movable contact of which is connected with the line 69 by the line 88. The movable contact of the switch mechanism 86 is acted upon by an electro-magnet 89, arranged in circuit with two of the terminals of the micro-motor shown conventionally at 90. This motor shown in the drawings is of the same type as the motors 22 and 23, and has three leads 91, 92 and 93, the leads 91 and 92 being at all times of opposite polarity, and being in electrical connection with the winding of the electro-magnet 89 through the lines 94 and 95.

While there is only one car switch mechanism 61, there are a plurality of floor switches, one of which is shown at 61a. This switch is in all respects identical with the car switch mechanism 61, having an opening switch 62a, a closing switch 63a and a stop switch 64a. Connected with the lines 69, 70, 71 and 85 respectively are branch lines 69a, 70a, 71a and 85a which extend throughout the height of the shaft. The line 69a is connected by a branch line 69b with one of the contacts of the opening switch 62a. The line 71a is connected by the branch line 71b with one of the contacts of the stop switch 64a. The line 70a is connected through the line 70b with one of the contacts of a switch mechanism 96 having a movable contact member adapted to be engaged by a shoe upon the car, and 130

through said switch mechanism 96 and the line 70c with the other contact of the stop switch 64a. The line 85a is connected with one of the contacts of the closing switch 63a by the line 85b.

5 The wiring of each hall switch is therefore identical with the wiring of the elevator car switch, with the exception that the normally open switch in the line to the stop switch will prevent the closing of any of the control circuits by the actuation of the hall switch unless a car is in a position at the floor where a particular floor switch is located so as to close a switch 96.

10 15 When floor switches are used, it is desirable to prevent the opening of any door until the elevator is located and at rest at a particular floor. This is due to the fact that when floor switches are used, no attendant travels in the car, a floor control mechanism being used by which the car may be started, when the conditions are such as is required by the car operating mechanism, and caused to travel to some particular floor.

20 25 Ordinarily, all freight elevator doors are equipped with what is known as an electrical interlock, which is a mechanism actuated as a result of the partial opening and complete closing of a door which will control the application of power to the car.

30 35 To guard against what is known as the "stealing of the car," or the interruption of the power for actuating the car while the car is in transit from one floor to another predetermined floor by the opening of the doors as the car passes an intermediate floor, I provide a switch mechanism in the line 70 which will be normally open while the car is in motion, but will be automatically closed when the

40 45 car comes to rest at any floor.

In the accompanying drawings, this switch mechanism is shown at 98 and is arranged in the line 70. The movable contact member of this switch is acted upon by an electro-magnet 99, energized by the circuit to the electric motor 100 for imparting travel to the car. This motor 100 is of the same type as the motors 22 and 23, and has three leads 101, 102 and 103, the leads 101 and 102 being at all times of dissimilar polarity and being in electrical connection through the lines 104 and 105 with the winding of the electro-magnet 99.

50 55 The switch 98 need be used only when floor switches are used, since when the car switch 61 is used, the switch mechanism 54 will prevent the application of power for opening or closing a door until the car is in a desired position.

60 65 My present invention has to do only with the electrical mechanism of a door operator, and I have, therefore, neither shown nor described any of the various mechanisms or attachments with which such doors may be equipped for purposes other than controlling

their operation. Such other attachments and devices are numerous, are subject to wide variation and are well known.

The operation of the herein described door operator is substantially as follows:—

70 When a car is approaching a floor and all the doors in a shaft are closed, the electrical conditions as to each door and in the penthouse control mechanism will be as shown in Fig. 3, the movable contacts of the door opening switch 36, 37 and 38, the door closing switch 48, 49 and 50 and the shaft switch 54 being open, and the switch 74 of the time limit switch 73 being closed. The stop switch 64 is normally closed, and the opening and closing switches of the car switch mechanism 61 are normally open.

75 80 85 As a car comes to rest at a door opening, the switch 54 is closed, either manually or automatically, through the shoe 56, thus connecting both motors 22 and 23 with the main power line 30, 31 and 32 extending throughout the shaft. When the switch 98 is used, this will also be closed under these conditions.

90 95 It being desired to open a door, the attendant merely punches, or forces in, the contact member of the opening switch 62. With the closing of this switch, current will flow from the line 47 through the lines 44 and 70, the stop switch 64, the wires 66 and 65, the opening switch 62, the line 69, the winding of the electro-magnet 57, and lines 67 and 68 to the negative lines 42 and 45. This will energize the electro-magnet 57, the attraction of the armature of which will close the door opening switches 36, 37 and 38 and also the switch 76. The closing of the switches 36, 37 and 38 permits current to flow through the lines 45, 46 and 47, the lines 42, 43 and 44, said switches 36, 37 and 38, the lines 39, 40 and 41 respectively and the main power lines 30, 31 and 32. The switch 54 being closed, power will flow from the main power line through the branch lines 33, 34 and 35 to the motors 22 and 23 respectively, thus simultaneously actuating both of these motors.

100 105 110 115 120 125 130 By reason of the wiring of the motors, the motor 22 will have clockwise, and the motor 23 will have contra-clockwise movement, thus actuating the sheaves 18 at opposite sides of the door so as to exert a pull upon the chains 17, and raise the upper section, as 12, of a door while permitting the lower section 12a of that door to descend until the hanger bar 14 thereof engages the truck bar stops 15. The sheave 18 at one side of the door will be rotated by the gears 26 and 27 and actuated by the motor 22 in one direction, and the sheave 18 at the other side of the door will be rotated by the gears 28 and 29 and actuated by the motor 23 in the opposite direction. Since the sections 12 and 12a of the door are substantially counterbalanced,

the power required for imparting this movement thereto is low. As the hanger bar 14 engages the truck stops 15, if the sheaves should be rotated beyond that required to 5 impart a full opening movement to the door, slippage can occur between each sheave and the co-operating chain 17 in a manner to prevent excess movement of the door. It is desirable, however, to prevent this condition, 10 or at least to limit it to as short an interval as possible, and it is for this reason that I provide the time limit switch 73.

It is desirable, when opening a door, for the door to have continual movement without 15 the use of a constant pressure opening switch in the car. In other words, it is desirable that the attendant shall be required to merely quickly push in the movable contact member of the opening switch, and then instantly release it and still have the holding magnet 57 continue to be energized for a time interval sufficient to ensure the complete opening movement of the door, or a predetermined amount of opening movement. The time limit 20 switch 73 is used for this purpose. When the electro-magnet 57 is energized, the movable contact of the switch 76 will be actuated to close a circuit which will energize the winding 72 of the electro-magnet of the time limit 25 switch 73. The circuit for energizing this winding 72 will be from the line 47, through the lines 44 and 70, stop switch 64, line 71, winding 72, switch 74, line 75, switch 76, line 77, line 69, the winding of the electro-magnet 30 35 57 and lines 67, 68 and 42 to the negative line 45. Hence the actuation of the opening switch 62 will momentarily energize the electro-magnet 57. The energizing of this electro-magnet 57 will not only close the door 40 opening switches 36, 37 and 38, but will also cause the winding 72 of the electro-magnet of the time limit switch to be energized at the same time, closing a circuit through the stop switch 64 to the electro-magnet 57 so as to 45 cause it to continue to be energized notwithstanding the interruption of the circuit at the switch 62.

As the electro-magnet 72 is energized, the traction of this magnet will be applied 50 through the core and cross bar 78 to the spring 81 and the plunger of the dash pot 82. Outward movement of the cross bar 78 and the rods 79 and 80 will be resisted by the sub-atmospheric pressure or suction within the cylinder of the dash pot, so that the outward movement of the plunger of the dash pot will be resisted and yet this plunger will have a very slow movement. The time interval before the sub-atmospheric pressure within the cylinder of the dash pot is relieved by the opening of the cylinder ports as a result of the movement of the plunger, may be accurately determined by the calibration of the 55 60 65 vent opening in said cylinder. As soon as

the pressure, however, is relieved, the cross bar 78 will be moved rapidly, thus developing sufficient tension in the spring 81 to overcome the tension in the spring 84 causing rapid movement of the lever 83 and the interruption of the circuit at the switch 74. This will immediately de-energize the electro-magnet 57 and also the electro-magnet 72. Consequently, the spring 84 will immediately close the switch 74. 75

The de-energizing of the electro-magnet 57 will result in the interruption of the circuits controlled by the switches 36, 37, 38 and 76, so that all of the circuits will be interrupted and will remain interrupted until the switch 62 has been again actuated. If the time interval for which the time limit switch 73 has been set is sufficient to permit the complete opening of the door, a further actuation of the switch 62 is unnecessary. If the time interval is not sufficient, however, a second actuation of the switch may be necessary. The switch 54 will remain closed so long as the elevator car is at the door opening. 80

When it is desired to close the door, the closing switch 63 is actuated by the attendant. This is preferably a constant pressure switch, or one which requires the attendant to manually hold it closed during the entire closing movement of the door. This is desirable. 85 There is little or no element of danger in opening a door. In closing a door there is an element of danger, particularly in a rapidly moving door, and by the use of a constant pressure switch the movement of the doors 100 may be stopped instantly by merely releasing the switch. 95

When the switch 63 is actuated, the electro-magnet 58 will be energized, the circuit to this magnet being from the line 47, through the leads 44 and 70, the stop switch 64, wire 66, closing switch 63, line 85 to one terminal of the winding of the electro-magnet 58, from the other terminal of this winding, through the lines 68 and 42 to the minus line 45. This energizing of the electro-magnet 58 will, through its armature 60, actuate the switches 48, 49 and 50 to close the circuit through the lines 51, 52 and 53 and the lines 40, 39 and 41 respectively, to the main power lines 31, 30 and 32 respectively, and through the switch mechanism 54 and the branch lines 33, 34 and 35 to the motors 22 and 23 respectively. 105

It will be noted that by the closing of the switches 48 and 49, the polarity of the current in the wires 30 and 31 of the main power line is reversed, thus causing a reversal of the direction of movement of the motors 22 and 23. Except for this change of polarity in the current in two of the wires, the circuit from the wires of the main power line to the motors 22 and 23 will be as heretofore described. The instant that the attendant releases the closing switch 63, the circuit to the electro- 110

magnet 58 will be interrupted, and the various switches 48, 49 and 50 will automatically open.

It is to be noted that the time limit switch 73 is not operative during the closing of the doors.

It is also to be noted that the chain 17 is an ordinary link chain and not a sprocket chain, and that the operative effect of the sheaves 10 upon this chain is dependent upon the weight of the two door sections at opposite ends of the connections passing about the sheaves. The minute that the lower door section comes to rest upon the truck bar stops 15, the weight 15 upon one side of the sheaves is relieved, and the subsequent application of power to the sheaves will merely result in relieving the frictional engagement between the sheave and the chain to an extent to prevent further 20 movement of the upper door section to an appreciable extent. The use of the time limit switch is to minimize possible overrunning of the sheave and preclude any possibility of 25 possible injury to the sheave and to the operator motors in the event that through accident, conditions should develop which would result in overrunning of this upper door section. Furthermore, the time limit switch permits 30 the use of a single control for limiting the operation of the actuation of any operator motors for a series of doors in a shaft, which very much simplifies and cheapens the installation since it avoids the use of individual time limit switches operated by each door.

If for any reason it is desired to interrupt the opening movement of a door, it is merely necessary for the operator to actuate the stop switch 64, which will immediately interrupt 35 all circuits in the operator, since the current for all circuits passes through this switch, excepting that of the initial opening circuit, due to the actuation of the opening switch 62.

If the operator be used in an automatic elevator, or one not requiring the presence of 40 an attendant in the car, a switch 61a is positioned on each floor. When a car approaches a floor, it actuates the movable contact member 97. This closes the switch 96 which will remain closed while the car is at the adjacent floor. The opening switch 62a, the closing switch 63a and the stop switch 64a may be actuated with the same results as the actuation of the switches 62, 63 or 64 of the car 45 switch 61. A repetition of the circuits is unnecessary.

The switch 98 is used when hall switches are included in an installation, to prevent the so-called "stealing" of a car, as before 50 described. When a car switch only is used, the presence or absence of this switch is immaterial, since it will always be closed whenever it is required to actuate a switch in the car. When a hall circuit is used, however, it 55 is desirable to prevent the actuation of any

hall switch while a moving car is at the floor where this switch is located.

The construction of the switch 98 is such that whenever power is being applied to the car, the winding of the electro-magnet 99 will be energized so as to open the switch 98. Since all of the circuits of the operator go through the line 70, this opening of the switch will prevent any actuation of the operator. Whenever the power to the motor 100 for 75 actuating the car is interrupted, however, then the switch 98 will automatically close so that power may be applied to the operator. The switch 98 is not to be considered as a remote operating control, but merely as a 80 safety factor for preventing the unauthorized actuation of the operator.

The micro-control, however, is a remote control for the operator and may be used in conjunction with the car or hall switch mechanism. The purpose of this micro-control is to relieve the operator of the necessity of actuating the opening switch 62, if the micro-mechanism control be used, or in the event of an automatic micro-control being used, to cause the actuation of this mechanism to be also effective in actuating the door operator. When the circuit to the micro-mechanism is closed in any manner, the winding of the electro-magnet 89 will be energized, thus 95 closing the switch 86. The closing of this switch will set up a circuit from the line 47, through the line 44, line 87, switch 86, line 88, line 69, magnet winding 57, lines 67, 68 and 42 to the negative line 45. The effect of energizing the electro-magnet 57 as a result of the closing of the switch 86, will be the same as when this magnet is energized as the result of the closing of the opening switch 62. The actuation of the micro-mechanism is like that 100 of the actuation of the switch 62, merely momentary.

Following the energizing of the electro-magnet 57 as a result of the closing of the switch 86, circuits will be established the 110 same as described in connection with the actuation of the switch 62, the initial closing of the circuit bringing into operation the time limit switch 73 with the same results as when the electro-magnet 57 is energized by the 115 actuation of the switch 62.

The wiring connections of the electro-magnet 89 are such as to ensure the energizing of the winding of the magnet irrespective of the direction of rotation of the motor by the 120 micro-mechanism.

When a car leaves a floor, the shoe 56 will be disengaged from the movable contact 55, thus opening the switch 54 and interrupting the circuit to the motors 22 and 23.

If the switch 98 be used, the application of power to the car will automatically interrupt all of the circuits controlled by the opening and closing circuits, together with the control circuits for said switches and the circuit to 125

the master time limit switch. The use of this switch 98, however, is desirable only with so-called automatic elevators.

It is to be noted that by the use of the 5 master time limit switch 73, the quantity of movement of any door in a shaft may be controlled by a single mechanism which may be located in the penthouse and form a part of the switchboard.

10 It will be noted that in an operator embodying the invention, each door is provided with its individual electric motor-driven mechanism for both opening and closing the door, and that a single mechanism for controlling the application of power to said individual motor equipments is used.

As heretofore stated, the master time limit switch 73 is used only in the holding circuit for controlling the door opening switch, and 20 a constant pressure switch is used in the holding circuit for operating the door closing switch. This is desirable in order to have the opening of the door a continuing movement requiring only the manual operation of a 25 control to initiate the movement, thus leaving the car operator free to do other things upon the car arriving at a given floor. When closing a door, however, it is desirable to have the operator's attention concentrated upon 30 the doors to avoid possible accident, so that the constant pressure switch may be advantageously used for controlling the holding circuit of the door closing switch.

It will be noted that the car switch mechanism 61 is a movable remote control, and that the various floor switches 61a are fixed remote controls, as is the micro-switch mechanism 86 and the car motor switch control mechanism 98. The control switch mechanisms 61 and 61a and the micro-switch mechanism 86 may all be used in the equipment, but are alternatively operable.

The switch mechanism 98 is used only when floor switches are used and has no operative 45 effect whatever when a car switch 61 only is employed.

In the event of the interruption of power to any door, the construction herein described will permit the manual opening of that door, 50 since under such conditions the sheaves are either permitted to turn freely with the rotor of the motor, or the chains 17 will have slippage in relation to the sheaves in the event of the jamming of the motor. This condition 55 will exist as to all doors in a shaft in the event of the interruption of the main source of power for the operator. With a penthouse motor, this manual operation is impossible without considerable work in order 60 to make the operator inoperative as to all of the doors in the shaft, or any door which was required to be opened. With a door of light weight, in the event of failure of one of the motors, the remaining motor will still operate 65 the door.

It is not my intention to limit the invention to the details of construction shown in the accompanying drawings. The wiring diagram of Fig. 3 is applicable to a particular construction of motor 22 or 23 and will be 70 varied when motors of other types are used.

Having described the invention, what I claim as new and desire to have protected by Letters Patent, is:—

1. A door operator embodying therein the 75 combination with guides within an elevator shaft, a series of elevator doors each having sections vertically and oppositely movable on said guides, connections between said sections at the opposite sides thereof, and sheaves 80 about which said connections pass, of an electric motor within the shaft associated with each of said sheaves, gearing connecting each of said motors with its associated sheave, a main electric power line extending adjacent 85 all of said cores, branch lines extending therefrom adjacent each door and connected with the motors adjacent such door, a normally open switch in each of said branch lines adapted to be operated only when a car is positioned adjacent said switch, pole changing 90 switches controlling the circuits to said main power line, electro-magnetic control mechanisms for said pole changing switches, and means whereby said control mechanisms may 95 be selectively actuated from a remote point.

2. A door operator embodying therein the 100 combination with guides within an elevator shaft, a series of elevator doors each having sections vertically and oppositely movable on said guides, connections between said sections at the opposite sides thereof, and sheaves 105 about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent 110 such door, a normally open switch in each of said branch lines adapted to be operated only when a car is positioned adjacent said switch, pole changing switches including 115 door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches 120 and in circuit with the electro-magnets of said master time limit switch and the electro-magnet of the control for said door opening switches, and means whereby the control mechanism for said door opening and said 125

door closing switches may be selectively actuated from a remote point.

3. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, and a remote control mechanism embodying therein a car switch mechanism including a normally open opening switch in circuit with the electro-magnet of one of said pole changing switches, and a normally open closing switch in circuit with the electro-magnet of the other of said pole changing switches.

4. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches controlling the circuits to said main power line, electro-magnetic control mechanisms for said pole changing switches, and a remote control for said control mechanisms embodying therein a car switch mechanism including a normally open opening switch in circuit with the electro-magnet of one of said pole changing switches, a normally open closing switch in circuit with the electro-magnet of the other of said pole changing switches, and a normally closed stop switch in the circuits controlled by said opening and said closing switches respectively.

5. A door operator embodying therein the combination with guides within an elevator shaft, a series of elevator doors each having sections vertically and oppositely movable on

said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, and a remote control mechanism embodying therein a car switch mechanism including a normally open opening switch in circuit with the electro-magnetic control mechanism for said door opening switches and the electro-magnet of said master time limit switch, means closing the circuit to said electro-magnet of said master time limit switch independently of said opening switches, and a normally open closing switch in circuit with the electro-magnet of the control mechanism for said door closing switches.

6. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet opera-

tive thereon and in circuit therewith, and a switch controllable by the electro-magnetic control for said door opening switches and in circuit with the electro-magnets of said master time limit switch and the electro-magnet of the control for said door opening switches, and a remote control mechanism embodying therein a car switch mechanism including a normally open opening switch in circuit with the electro-magnetic control mechanism for said door opening switches and the electro-magnet of said master time limit switch, a normally open closing switch in circuit with the electro-magnet of the control mechanism for said door closing switches, and a normally closed stop switch in circuit with said opening and said closing switch respectively, and with the electro-magnet of said master time limit switch.

7. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, a remote control mechanism embodying therein a car switch mechanism including a normally open opening switch in circuit with the electro-magnetic control mechanism for said door opening switches and the electro-magnet of said master time limit switch, means closing the circuit to said electro-magnet of said master time limit switch independently of said opening switch, and a normally open closing switch in circuit with the electro-magnet of the control mechanism for said door closing switches, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and normally closed means in a branch circuit from the means closing the circuit to said electro-magnet of said master time limit switch, and a normally open shaft switch in the circuits controlled by the opening and closing switches of said hall switch mechanism.

8. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is

ciated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, a remote control mechanism embodying therein a car switch mechanism including a normally open opening switch in circuit with the electro-magnetic control mechanism for said door opening switches and the electro-magnet of said master time limit switch, means closing the circuit to said electro-magnet of said master time limit switch independently of said opening switch, and a normally open closing switch in circuit with the electro-magnet of the control mechanism for said door closing switches, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and normally closed means in a branch circuit from the means closing the circuit to said electro-magnet of said master time limit switch, and a normally open shaft switch in the circuits controlled by the opening and closing switches of said hall switch mechanism.

9. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is

- positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control 10 and for said door opening switches, a remote control mechanism embodying therein a car switch mechanism including a normally open opening switch in circuit with the electro-magnetic control mechanism for said door opening switches and the electro-magnet of said master time limit switch, a normally open closing switch in circuit with the electro-magnet of the control mechanism for said door closing switches, and a normally closed 20 stop switch in circuit with said opening and said closing switch respectively, and with the electro-magnet of said master time limit switch, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and a normally open shaft switch in the circuits controlled by both switches of said hall switch mechanism, and a normally closed electro-magnetic switch, the contacts of which are in the circuit controlled by the opening switch of the car switch mechanism, and the electro-magnet of which is energized as a result of the closing of the circuit to a motor for actuating the car. 25
10. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, and a plurality of selectively actuated remote controls for said control mechanisms embodying therein respectively a car switch mechanism including a normally open opening switch in circuit with the electro-magnet of one of said pole changing switches, and a normally open closing switch in circuit with the electro-magnet of the other of said pole changing switches, and a normally open magnetic switch the contacts of which are in circuit with the electro-magnet of said door opening switches, and the magnet of which is in circuit with the source of power for actuating the micro-mechanism of an elevator equipment. 50
11. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches controlling the circuits to said main power line, electro-magnetic control mechanisms for said pole changing switches, and a remote control for said control mechanisms embodying therein a car switch mechanism including a normally open opening switch 55

in circuit with the electro-magnet of one of said pole changing switches, a normally open closing switch in circuit with the electro-magnet of the other of said pole changing switches, a hall switch adjacent each door embodying therein a normally open opening switch in a branch circuit from the circuit controlled by the opening switch of the car switch mechanism, and a normally open closing switch in a branch circuit from the circuit controlled by the closing switch of said car switch mechanism, a normally open shaft switch in the circuits controlled by both switches of said hall switch mechanism, and a normally closed electro-magnetic switch, the contacts of which are in the circuit controlled by the opening switch of the car switch mechanism, and the electro-magnet of which is energized as a result of the closing of the circuit to a motor for actuating the car. 60

11. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, and a plurality of selectively actuated remote controls for said control mechanisms embodying therein respectively a car switch mechanism including a normally open opening switch in circuit with the electro-magnet of one of said pole changing switches, and a normally open closing switch in circuit with the electro-magnet of the other of said pole changing switches, and a normally open magnetic switch the contacts of which are in circuit with the electro-magnet of said door opening switches, and the magnet of which is in circuit with the source of power for actuating the micro-mechanism of an elevator equipment. 65

12. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches controlling the circuits to said main power line, electro-magnetic control mechanisms for said pole changing switches, and a remote control for said control mechanisms embodying therein a car switch mechanism including a normally open opening switch 70

- each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, and a plurality of selectively actuated remote controls embodying therein respectively a car switch mechanism including a normally open opening switch in circuit with the electro-magnetic control mechanism for said door opening switches and the electro-magnet of said master time limit switch, means closing the circuit to said electro-magnet of said master time limit switch independently of said opening switch, and a normally open closing switch in circuit with the electro-magnet of the control mechanism for said door closing switches, a normally open magnetic switch the contacts of which are in circuit with the electro-magnet of said door opening switches, and the magnet of which is in circuit with the source of power for actuating the micro-mechanism of an elevator equipment, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and normally closed means in a branch circuit from the means closing the circuit to said electro-magnet of said master time limit switch, a normally open shaft switch in the circuits controlled by the opening and closing switches of said hall switch mechanism, and a normally closed electro-magnetic switch, the contacts of which are in the circuit controlled by the opening switch of the car switch mechanism, and the electro-magnet of which is energized as a result of the closing of the circuit to a motor for actuating the car.
13. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, gearing connecting each of said motors with its associated sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, and a plurality of selectively actuated remote controls embodying therein respectively a car switch mechanism including a normally open opening switch in circuit with the electro-magnetic control mechanism for said door opening switches and the electro-magnet of said master time limit switch, means closing the circuit to said electro-magnet of said master time limit switch independently of said opening switch, and a normally open closing switch in circuit with the electro-magnet of the control mechanism for said door closing switches, a normally open magnetic switch the contacts of which are in circuit with the electro-magnet of said door opening switches, and the magnet of which is in circuit with the source of power for actuating the micro-mechanism of an elevator equipment, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and normally closed means in a branch circuit from the means closing the circuit to said electro-magnet of said master time limit switch, a normally open shaft switch in the circuits controlled by the opening and closing switches of said hall switch mechanism, and a normally closed electro-magnetic switch, the contacts of which are in the circuit controlled by the opening switch of the car switch mechanism, and the electro-magnet of which is energized as a result of the closing of the circuit to a motor for actuating the car.
14. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with each of said sheaves, a large gear carried by and rotatable with each of said sheaves, a small gear carried by each of said motors and enmeshed with a large gear respectively, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches including door opening switches and door closing switches controlling the circuits to said main power line, electro-magnetic control mechanisms associated respectively with said door opening and said door closing switches, a master time limit switch, including a normally closed switch mechanism, an electro-magnet operative thereon and in circuit therewith, and a switch controllable by the electro-magnetic control for said door opening switches and in circuit with the electro-magnets of said master time limit switch and the electro-magnet of the control for said door opening switches, and a plurality of selectively actuated remote controls embodying therein respectively a car switch mechanism including a normally open opening switch in circuit with the electro-magnetic control mechanism for said door opening switches and the electro-magnet of said master time limit switch, means closing the circuit to said electro-magnet of said master time limit switch independently of said opening switch, and a normally open closing switch in circuit with the electro-magnet of the control mechanism for said door closing switches, a normally open magnetic switch the contacts of which are in circuit with the electro-magnet of said door opening switches, and the magnet of which is in circuit with the source of power for actuating the micro-mechanism of an elevator equipment, a hall switch adjacent each door, including a normally open opening switch in a branch circuit from the circuit controlled by the opening switch of the car switch mechanism, a normally open closing switch in a branch circuit from the circuit controlled by the closing switch of said car switch mechanism, and normally closed means in a branch circuit from the means closing the circuit to said electro-magnet of said master time limit switch, a normally open shaft switch in the circuits controlled by the opening and closing switches of said hall switch mechanism, and a normally closed electro-magnetic switch, the contacts of which are in the circuit controlled by the opening switch of the car switch mechanism, and the electro-magnet of which is energized as a result of the closing of the circuit to a motor for actuating the car.

cuits to said main power line, electro-magnetic control mechanisms for said pole changing switches, and means whereby said control mechanisms may be selectively actuated from a remote point.

15. A door operator embodying therein the combination with guides within an elevator shaft, a series of elevator doors each having sections vertically and oppositely movable on said guides, connections between said sections at the opposite sides thereof, and sheaves about which said connections pass, of an electric motor within the shaft associated with a sheave, gearing connecting said motor with its associated sheave, a main electric power line extending adjacent all of said doors, a branch line extending therefrom adjacent each door and connected with the motor adjacent such door, a normally open switch in each of said branch lines, means carried by an elevator car adapted to co-operate with any of said normally open switches, whereby the circuit from said main line to a motor operative upon any door can be closed only when a car is positioned adjacent said switch, pole changing switches controlling the circuits to said main power line, electro-magnetic control mechanisms for said pole changing switches, and means whereby said control mechanisms may be selectively actuated from a remote point.

16. A door operator embodying therein the combination with guides within an elevator shaft, a series of elevator doors each having sections vertically and oppositely movable on said guides, connections between said sections at the opposite sides thereof, and sheaves mounted upon said guides about which said connections pass, of an electric motor mounted upon one of said guides adjacent a sheave, gearing connecting said motor with said sheave, a main electric power line extending adjacent all of said doors, a branch line extending therefrom adjacent each door and connected with the motor adjacent such door, a normally open switch in each of said branch lines adapted to be operated only when a car is positioned adjacent said switch, pole changing switches controlling the circuits to said main power line, electro-magnetic control mechanisms for said pole changing switches, and means whereby said control mechanisms may be selectively actuated from a remote point.

17. A door operator embodying therein the combination with guides within an elevator shaft, a series of elevator doors each having sections vertically and oppositely movable on said guides, connections between said sections at the opposite sides thereof, and sheaves mounted upon said guides respectively about which said connections pass, of an electric motor mounted upon said guides respectively adjacent said sheaves, gearing connecting said motors respectively with the adjacent

sheave, a main electric power line extending adjacent all of said doors, branch lines extending therefrom adjacent each door and connected with the motors adjacent such door, a normally open switch in each of said branch lines adapted to be operated only when a car is positioned adjacent said switch, pole changing switches controlling the circuits to said main power line, electro-magnetic control mechanisms for said pole changing switches, and means whereby said control mechanisms may be selectively actuated from a remote point.

In witness whereof I have hereunto affixed my signature this 23d day of August, 1929.

ROBERT S. PEELLE.
